UNITED STATES PATENT OFFICE.

HENRY B. ABEL, OF VALLEY STREAM, NEW YORK.

CATALOGUE.

Application filed May 25, 1922. Serial No. 563,533.

To all whom it may concern:

Be it known that I, HENRY B. ABEL, a citizen of the United States, and a resident of Valley Stream, in the county of Nassau and State of New York, have invented a new and Improved Catalogue, of which the following is a full, clear, and exact description.

This invention relates to publications and 10 refers particularly to an improved construction wherein the publication is sealed and ready for mailing without the use of an envelope.

The invention also refers to a publication 15 which not only is bound on opposite sides or edges to provide a proper mailing matter but to a construction wherein one of the bound ends or edges may be torn off for providing two publications having certain 20 relation to each other.

The object of the invention is to provide an improved construction for publications wherein the same is automatically ready for mailing when completed.

25 Another object of the invention is to provide a publication which has a double binding and which, therefore, is capable of tearing into two sections for independent use.

A still further object of the invention is 30 to provide a publication in the nature of a catalogue or similar publication with a large and small section removably connected together and bearing either the same subject matter or related subject matter.

35 In the accompanying drawing—

Figure 1 is an elevation of a publication disclosing one embodiment of the invention.

Figure 2 is a view similar to Figure 1 but 40 with the publication divided into two parts and each part open somewhat for illustrating the co-ordination therebetween.

Figure 3 discloses a slightly modified form of the invention to that shown in Figure 1.

45 Figure 4 is a view of the opposite side of the page to that shown in Figure 3.

In the accompanying illustration, the invention has been embodied in a catalogue, though it may be embodied in a booklet or 50 pamphlet or some other form of publication without departing from the spirit of the invention and, therefore, the term "catalogue" is to be understood as meaning any suitable booklet, folder, pamphlet or other publication.

55 In forming the catalogue as illustrated,

it is intended to present a construction which will be acceptable by the postal authorities by merely adding a stamp and a proper address. In addition to presenting 60 proper mail matter, it is also intended to present a catalogue having comparatively large views of articles to be sold with certain identifications thereon and a removable section or end portion having a miniature 65 of the matter presented in the main catalogue. This miniature may be readily placed in a lady's handbag or in a pocket for reference while the large catalogue may be retained at the home of the party receiving 70 the catalogue so as to be ready for reference at any time.

Referring to the accompanying drawing by numerals, 1 indicates the main catalogue and 2 the removable section which is preferably integral with the main catalogue. In printing the catalogue, the section 2 is printed at the same time and the various leaves of the catalogue are assembled and secured together by suitable securing means 3 and 4 at the opposite ends though if desired, they could be secured together at the sides with the section 2 arranged on the side. However, when the parts are arranged as shown in the accompanying drawing, the ends are connected together by any suitable securing means which will leave the sides open and, consequently, permit the postal authorities to thoroughly inspect the publication. 85

In the catalogue shown, different articles 90 are presented with certain identification numbers so that when a person desires to secure any of these articles they may do so readily by mentioning the number of the article desired. In order that the customers may not be compelled to carry the large catalogue 1 with them to the store, section 2 is torn off along the weakened line 5 and is placed in the pocket or handbag. This section is provided with a miniature of the 95 various pictures, numbers and other information on the catalogue 1. In addition, the outside of the section 2 is left principally blank so as to receive an address 6 while the stamp 7 is preferably arranged near the 100 address 6 and if desired may be positioned either on the catalogue 1 or on the section 2. The weakened line 5 may be perforations or any other form of weakening which will ordinarily hold the parts together but which 110 may be readily torn. Arranged near the extreme edge of the section 2 is a second weak-

ened line 5' provided so that any of the pages of the section 2 may be removed and left with the storekeeper or used by the customer in any way desired.

In addition to having miniatures of the pictures and other matter in the catalogue 1, section 2 may have coupons printed thereon or the coupons may be provided as a substitute for the miniature representation of 10 catalogue 1, said coupons having certain value in relation to the matter disclosed in the catalogue. For instance, by presenting a coupon from the section 2, the purchaser is allowed a certain discount from articles 15 published in the catalogue. In this way the publisher of the catalogue will know that the catalogue has produced the desired result of calling attention to the goods displayed.

An additional function for the section 2 is to compel the reciprocant to tear this section off of the catalogue 1 in order to properly examine the catalogue. When the section 2 is once torn off the reciprocant will readily observe that it is substantially a replica of the catalogue 1 or is a book of coupons or some other desirable article worthy of saving in case the reciprocant desires to purchase any of the goods displayed.

It will be noted that by having the fastening means 3 and 4 on the opposite ends of the catalogue, each part is left with a securing means when the section 2 is removed, namely, the catalogue 1 is still provided with a securing means 3 while section 2 is still 25 provided with a securing means 4. When the section has been removed, two books or pamphlets are thus formed; one of a size to retain in the home and the other of a size to put in a pocket or handbag.

40 In Figures 3 and 4 a modified form of the invention is shown wherein sections 8 and 9 are provided on the side of each page of the catalogue instead of on the end as shown in Figures 1 and 2. The fastening means 3 and 4 are therefore arranged on the sides instead of the ends of the catalogue and in addition there are two sections 8 and 9 for each leaf which is not true in the structure shown in Figure 1. Section 8 shows on the obverse 50 side as in Fig. 3 the same picture and information found on the obverse side of the page in the catalogue and on the reverse side as shown in Fig. 4 certain wording is provided which will advertise certain facts and 55 which will make the particular section good as a coupon which will have a certain discount value. Section 9 is a section similar to section 8, but shows on its reverse side the picture shown in the reverse side of the leaf, as shown in Fig. 4, and on the obverse side, or the side on which section 8 shows its picture, shows the advertising matter relating 60 to the picture shown in the rear of the leaf. Thus section 8 shows at its front side a miniature figure of the figure at the front of

the leaf and at its rear side it shows the advertising matter relating to that figure, while the section 9 shows at the front side the advertising matter of the figure shown in the rear of the leaf and at its rear shows a miniature figure of that figure.

By this construction and arrangement a person may tear out section 8 because the person desires to purchase something on the obverse side of the page containing said section and when tearing out this section will not interfere with section 9 which shows on the obverse side of the sheet a miniature of the furniture on said obverse side. In this way, a coupon is provided for each side of 75 each sheet and in addition an independent miniature is provided of the matter advertised on each side of each sheet of the catalogue. Of course, if it is desired, the two sections 8 and 9 may be removed by tearing 80 along the line 10 and the sections retained as one book though preferably the sections are torn apart along the line 11 so that there will be two books, one book showing coupons and replicas of one page of each leaf of the 85 catalogue and the other showing a coupon and replica of the opposite page of each leave of the catalogue.

What I claim is:

1. A catalogue of the character described, 90 two permanent bindings placed on diametrically opposite ends, the sides of the catalogue not provided with the bindings being open to permit ready inspection, means provided near one end of the catalogue for permitting ready tearing of the catalogue into two sections with binding means on each section, and further means provided between said first-mentioned means and the binding means at one section for tearing the leaf 95 from each section.

2. In a catalogue of the character described, a body structure having a catalogue section and a removable section, said sections having interdependent information placed thereon, and a weakened line arranged adjacent said sections providing a tearing line whereby said sections may be torn apart without injuring either section, and a binding means for each of said sections at opposite ends thereof.

3. In a catalogue of the character described, a body structure having representations of one kind printed on one section and co-acting representations or legends printed on a second section, said body structure having a weakened line between said sections, said section mentioned section having an address space provided on its front cover, and means for securing the leaves of said sections together at the opposite ends of said body structure whereby when the body structure is torn along said weakened line each section will have a binding along one edge.

4. In a catalogue or other matter adapted to be mailed, means for securing opposite edges of the catalogue together, and means forming a pair of parallel and spaced weakened lines near one of said securing means.
5. A catalogue of the character described, comprising a body provided with a plurality of leaves, said leaves being provided with a pair of parallel weakened lines near one edge of the body, and securing means arranged adjacent one of said weakened lines and adjacent the opposite edge of the catalogue to said weakened line.
6. A catalogue of the character described, comprising a body provided with a plurality of leaves, each of said leaves having a pair of sections printed thereon adjacent one edge, said sections having on one face a coupon and on the opposite face a replica of one side of the leaf to which it is attached, said leaves being provided with weakened lines whereby said sections may be readily torn from the remaining part of the leaf.
7. A catalogue of the character described, comprising a body provided with a plurality of leaves, said leaves being secured together along opposite edges by a plurality of fastening means, said leaves being provided with a pair of parallel weakened lines near one edge of the body and with a trans-
- verse weakened line intermediate the ends of said parallel weakened lines whereby said weakened lines substantially include two sections, each section containing a replica of one face of said leaf on one of its faces and a coupon on the opposite face.
8. In a catalogue of the character described, a body provided with a plurality of leaves, means for securing said leaves together on opposite edges, each of said leaves being provided with advertising matter on each face, and weakened lines arranged on each of said leaves for dividing the leaves into a main body and two removable sections, one of said sections containing a replica of the advertising matter on one face of the leaf, and the other a replica of the advertising matter on the other face of the leaf.
9. A catalogue of the character described, comprising a volume formed of a plurality of sheets, each showing a large figure and a miniature replica of that figure adjacent thereto, and binding means at opposite edges of said body, together with means at each side forming a weakened line between the large and the miniature figures to permit a separation of the two into a large and a small volume.

HENRY B. ABEL.
